NOZZLE FOR ENGINES WORKING WITH AIRLESS FUEL INJECTION

Application filed April 16, 1928, Serial No. 270,525, and in Great Britain May 6, 1927.

This invention relates to nozzles for oil engines working with airless injection and has for its primary object to lessen the tendency of the nozzle to become choked.

5 In accordance with the invention there is interpolated between the valve seat and the sprayer holes a member incorporating restricted and tortuous channels or passages along which the fuel is constrained to flow 10 on its way to the atomizing sprayer holes, the number of the channels or passages aforesaid which are individually small in cross section, being so far in excess of the number of atomizing grooves that the interpolated 15 member acts as a filter, or in other words arrests solid particles which otherwise might choke the atomizing sprayer holes, it being understood that the choking of even a number of the filter channels or passages will not 20 seriously impair the action of the nozzle. The nozzle preferably comprises an outer member from the hollow interior of which the holes lead, and a filter member which fits closely in said hollow interior of said outer 25 member and has longitudinal and transverse grooves in its surface through which the oil is adapted to be fed to said sprayer holes. The oil thus has a very considerable cooling effect on the nozzles. Alternatively however 30 the filter member may fit loosely in said hollow interior and may have an axial bore hole extending throughout most of its length and radial holes extending from said bore hole to the surrounding clearance. In this 35 case the oil is adapted to be fed into said bore hole and thence through said radial holes to the surrounding clearance from which the sprayer holes lead.

But in order that the invention may be 40 more readily understood and easily carried into effect it will now be further described with the aid of the accompanying drawings, in which Fig. 1 is a vertical section of one constructional form of nozzle embodying the 45 improvements. Fig. 2 is an underside plan of the filter shown in Fig. 1, Fig. 3 a plan and Fig. 4 a transverse section of such filter. Fig. 5 is a view similar to Fig. 1 of an alternative form of filter and Fig. 6 is a section 50 at the line 6-6 of Fig. 5.

Referring first to Figs. 1 to 5, the nozzle 1—which projects vertically downwards in the usual way—has a relatively large circular bore hole in which the filter 2 is contained, from which bore hole extends one centre 55 sprayer hole 3 through which the oil from the filter is adapted to be projected in a finely atomized and whirling spray and a number of more or less radial sprayer holes 4 through which more penetrating jets are adapted to 60 be projected.

The filter 2 is of roughly cylindrical formation and fits closely into the said bore of the nozzle 1. The lower end 5 of said filter is slightly tapered in such a way that a small 65 annular clearance 6 is provided between the same and the wall of the bore hole, which clearance communicates with the radial sprayer holes 4. The surface of the filter is screw threaded throughout practically the 70 whole of its length above the tapered portion 5 and has also formed therein a number (say twelve) of circumferentially spaced longitudinal grooves. Alternate grooves 7 of this number (hereinafter termed the inlet 75 grooves) communicate at the upper ends with the oil supply source, being extensions of the holes 8 in the filter head 9, but at their lower ends stop short of the taper portion 5 of the filter. The remaining grooves 10 80 (hereinafter termed the outlet grooves) extend down to said taper portion and then communicate with the annular clearance 6 aforesaid, but at their upper ends stop short of the upper termination of the screw thread. 85

The bottom extremity of the filter is formed to a flat inverted cone and the bottom extremity of the nozzle bore hole is made correspondingly concavo-conical. The said conical extremity is truncated and thus a small 90 flat conical central clearance space 11 is formed immediately above, and in direct communication with, the centre sprayer hole 3 of the nozzle. This clearance 11 communicates with the annular space 6 by way of two diametrically opposite grooves 12 which run tangentially to said clearance. 95

In operation the oil is fed from above into the inlet grooves 7 through the holes 8, and when said grooves 7 are full passes by way of 100

the screw threads into the outlet grooves 10 and thence into the clearance space 6. From the space 6 some of the oil will be projected through the radial holes 4 in the form of 5 penetrating jets. The remainder will pass through the bottom tangential grooves 12 into the central clearance space 11 and then will be projected in the form of a finely atomized spray through the centre sprayer hole 3. 10 By virtue of the tangential disposition of the grooves 12 the oil projected through the hole 3 is rotated about the line of projection as axis and is thus the more finely atomized and the whirling action of the jet causes air 15 turbulence in the combustion space.

The mode of feeding the oil into the inlet grooves 7 through holes 8 in an enlarged upper end of the filter is convenient, as the said end 9 can be firmly seated in a corresponding enlarged portion of the nozzle bore 20 hole.

It will be seen that by the construction above described the oil is filtered with a minimum of resistance and that the oil is enclosed, within the nozzle itself, between the 25 supply valve 13 and the sprayer holes 3, 4, is only of very small quantity and is utilized to give the maximum cooling effect, thus tending to prevent the formation of carbon 30 on the nozzle.

As an alternative, the filter may fit loosely in the bore hole of the nozzle so that, as in the modification shown in Figs. 5 and 6, a clearance is provided around said filter. In 35 this example, the longitudinal grooves and screw threads of the first described construction, are replaced respectively by an axial bore 14 and a number of radial holes 15 extending therefrom to said surrounding clearance. The axial bore hole 14 stops short of the lower end of the filter but passes through 40 the enlarged upper end 9 where it is adapted to receive the oil from the valve. It will be seen that in this case the oil passes into said 45 central bore hole 14 and through the radial holes 15 into the clearance space and thence to the sprayer holes as before. Fig. 5 illustrates a somewhat different formation of the lower end of the filter and complementary 50 nozzle portion, which modification may be incorporated in the construction of Fig. 1 just as the construction of the corresponding parts in Fig. 1 may be adopted in the construction according to Fig. 5.

55 As a further means of preventing over heating of the nozzle the same is surrounded and protected by an annular projection 16 from the cap 17 in which the whole nozzle including the supply valve 13 is mounted. This 60 projection 16 is in turn surrounded and protected by means of a second annular projection 18 of a water cooled sleeve in which said cap 17 and also the casing (not shown) of the needle valve 13 and oil supply conduits 65 are mounted. Suitable air spaces are pro-

vided at 22 between the nozzle 1 and the cap projection 16 as well as at 22^x between the said projection 16 and the sleeve projection 18.

What I claim is:—

1. An oil engine nozzle of the kind referred to comprising a hollow outer member having a whirling sprayer hole encircled by a series of auxiliary holes formed therein, and a peripherally cross-channeled member having a tapered end arranged in the outer member covering the sprayer hole and leaving a clearance space around the said tapered end from which said auxiliary holes extend, the extremity of said member having diametrically opposite grooves extending tangentially from the sprayer hole to the clearance space aforesaid. 70

2. An oil engine nozzle of the kind referred to comprising a hollow outer member having a whirling sprayer hole formed therein, surrounded by additional penetrating sprayer holes, and a filter member having a tapered end arranged in the outer member covering the sprayer hole and leaving a clearance space around the said tapered end communicating with the penetrating sprayer holes, the extremity of such filter member having diametrically opposite grooves extending tangentially from the whirling sprayer hole to the clearance space aforesaid. 80

3. A fuel nozzle for an oil engine working with an airless injection, embodying a valve, a valve seat, a nozzle plate therebeyond with sprayer ejection holes therein, and filtering means interposed between the valve seat and sprayer holes, said means comprising a member having a plurality of longitudinal channels crossed by a series of transverse channels in its outer periphery providing tortuous paths along which the fuel finds its way to the sprayer holes. 90

4. A fuel nozzle for an oil engine working with airless injection, embodying a hollow outer member in which sprayer ejection holes are formed, and a filter member fitted in said hollow member and formed with a series of transverse and longitudinal grooves within which the fuel may flow therealong and from various points in the length thereof to the sprayer holes. 100

Signed at West Hartlepool, in the county of Durham, this sixth day of March, 1928.
